UNITED STATES PATENT OFFICE.

WILLIAM H. STOKES, OF STOKESVILLE, GEORGIA.

FENCE-POST FOR WIRE FENCING.

1,181,938.

Specification of Letters Patent.

Patented May 2, 1916.

Application filed June 24, 1914. Serial No. 846,958.

To all whom it may concern:

Be it known that I, WILLIAM H. STOKES, a citizen of the United States, residing at Stokesville, in the county of Charlton and State of Georgia, have invented certain new and useful Improvements in Fence-Posts for Wire Fencing; and I do hereby declare the following to be a full, clear, and exact description of the invention, such as will enable others skilled in the art to which it appertains to make and use the same.

This invention relates to fence posts and more particularly to metal posts, and has for one of its objects the provision of a post whereby any number of line wires may be secured thereto, or wire fabric may be secured to the posts with equal efficiency.

A further object of this invention resides in the construction of a fence post provided with adjustable securing means, whereby any number of line wires or wire fabric of any size of mesh may be readily secured to the posts without the necessity of making any alterations in the post construction.

A still further object of this invention resides in the provision of a fence post which may be inserted in a plastic base, or set within a hole in the ground, and the hole filled with cement or dirt, or the post may be used as a driven post, in the latter instance being especially adapted for marshy ground. And a still further object of this invention resides in the provision of a metal fence post which is simple in construction, of light weight, efficient and durable in purpose, and which can be manufactured and sold upon the market at a normal cost.

These and other objects will more fully appear as the nature of the invention is more clearly understood by the construction, combination and arrangements of the parts thereof as described in the following specification, defined in the appended claim and illustrated in the accompanying drawings, in which,

Figure 1, is a front view of the post showing the same in set position and having one of the line wires secured thereto. Fig. 2, is a side view of the post showing the manner of riveting the bars together and the arrangement of the driving point and the anchor plate at the bottom of the posts. Fig. 3 is a vertical sectional view on line 3—3 of Fig. 1, partly broken away, showing the spacing lugs between the posts and the ad-

justable securing means for the wires. Fig. 4, is a horizontal sectional view on line 4—4 of Fig. 2, showing the manner of assembling the various parts of the post construction.

The posts constituting this invention may be formed of cast iron, wrought iron, steel or any other suitable metal, and while the preferred form of bars is here shown, namely angle bars of L-shape in cross section, it is to be understood that the bars may be channel shaped, U-shaped or any other desired form in cross section.

Referring to the drawings 1—1 denotes the angle bars, preferably L-shaped in cross section and longitudinally tapered, the bars being positioned in parallelism to each other in a manner that one of the flanges of each of the bars face each other, and between these flanges at predetermined points are the spacing lugs or collars 2, and through the spacing lugs or collars 2 and correspondingly registering apertures formed in the facing flanges of the bars are the bolts or rivets 3, for securing the respective bars in fixed parallel relation to each other, the lugs or collars 2 being of sufficient length to provide the space 4 between the bars.

The lower ends of the bars are tapered to provide the pointed ends 5, and disposed in vertical edgewise position between the bars 1 within the space 4 is provided a plate 6, the width of which is greater than the width of the flanges of the bars 1, the lower portion of the plate 6 being tapered to provide the point 7. The tapered end 5 of bars 1, and the vertical edgewise position of the plate 6, together with the point 7 of the plate 6 enables the post to be readily driven into the ground, when the same is used as a driven post, the upper surface of the plate 6 being horizontal as shown at 8 provides a broad surface for receiving the blows of a maul, sledge hammer or other driving means for driving the post into the ground at the initial operation.

The point 7 of the plate 6 projects for a distance below the pointed ends 5 of the bars 1, and the plate 6 is rigidly secured within the space 4 between the bars 1 by the bolts or rivets 9, preferably rivets.

Between the bars 1 within the space 4 and at a point remote from the lower end of the post is the transversely positioned anchor plate 10, the plate 10 being rigidly secured in vertical edgewise position within

the space 4 and between the bars 1 by the bolts or rivets 11, the anchor plate 10 being in vertical alinement with the plate 6, and preferably positioned at a point upon the 5 post wherein the same will lie slightly beneath the surface of the ground, for maintaining the post in strict vertical position by preventing lateral displacement of the post, and owing to the vertical edgewise 10 positioning of the plate 10, the post is more readily driven into the ground.

For securing the wires or the fabric of the fence line to prevent lateral movement of hook bolts 13, only one bolt here being 15 shown, these bolts being positioned within the space 4 between the facing flanges of the bars 1 and vertically adjustable within the space 4, whereby any number of hook bolts 13 may be used and the same positioned 20 at any point along the post for securing any number of wires desired, or for positioning the bolts 13 for engaging the twisted portions of the mesh of the wire fabric, the bolts 13 being provided at the end opposite 25 the hook portion with the thread 14 and retained in secured adjusted position by the nut 15, screw threaded thereon and bearing against the rear edges of the flanges of the bars 1, the hook end 13 being designed to 30 engage the line wire 16, and by screwing the nut 15 over the thread end 14 of the bolt, the hook end impinges the wire 16 against the front of the post and firmly retains the wire 16 upon the post.

35 I desire to here state that while I have shown the post constituting this invention as being driven or set in the ground, I do not limit myself to this exact application as the base of the post may be set in a mold 40 and cement or other plastic material, molded upon the lower end of the post thus providing a metal post having a plastic base without having to make any alterations in the construction of the post, as the angle 45 bars 1 together with the plate 6, and the anchor plate 10 will be embedded within the plastic composition and thus add materially to the efficiency and strength of the post.

While I here have shown and described

the preferred form of my invention, I hereby 50 reserve the right to make such alterations and variations therein from time to time as I may deem expedient, and which will neither depart from the spirit of this invention nor the scope of the claim. 55

Having thus fully described my invention 60 what I claim as new and desire to secure by Letters Patent, is:—

A metal fence post, comprising a pair of bars formed of L-shaped angle iron and having 65 their lower ends beveled to provide sharp points, said bars having one of their angle portions positioned face to face in spaced parallelism in a manner to form a post substantially T-shaped in cross section 70 and providing a broad attaching face, means for maintaining said bars in fixed spaced relation, a flat base plate rigidly secured in vertical edgewise position between the opposing faces at the lower pointed ends of 75 said bars, said base plate having a horizontal upper portion and a sharp V-shaped point projecting slightly beyond the pointed ends of said bars and co-operating therewith to provide for the ready driving of the post into the ground, and a flat elongated anchor plate horizontally disposed and rigidly secured in vertical edgewise position between the opposing faces of said 80 bars above and in vertical alinement with said base plate, said base plate, said anchor plate, and said spaced parallel angle portions of said bars being transversely disposed relative to the fence line and coacting with each other to prevent lateral movement of the post in the longitudinal direction of the line of the fence, the broad attaching face of the post being parallel with the fence line to prevent lateral movement 85 of the post transversely of the line of fence. 90

In testimony whereof I have signed my name to this specification in the presence of two subscribing witnesses.

WILLIAM H. STOKES.
